MACHINE FOR DYEING YARN AND THE LIKE

Filed Nov. 16, 1928

UNITED STATES PATENT OFFICE

ARTHUR E. BYRD, OF MILWAUKEE, WISCONSIN, ASSIGNOR TO PHOENIX HOSIERY COMPANY, OF MILWAUKEE, WISCONSIN, A CORPORATION OF WISCONSIN

MACHINE FOR DYEING YARN AND THE LIKE

Application filed November 16, 1928. Serial No. 319,932.

This invention relates in general to a machine for dyeing yarn or other textile or fibrous material and is particularly designed for imparting to the material a mottled or variegated appearance whereby different portions of the material are tinted or colored differently in a uniform manner. By dyeing or coloring thread in this way and subsequently knitting or weaving it into fabric an attractive mottled or multi-colored fabric may be produced by a conventional knitting or weaving method in machines.

One of the principal objects of the present invention is to provide a machine for dyeing yarn or the like in this manner and which is of simple and durable construction, which is reliable and effective in operation and which may be manufactured and operated at a comparatively slight expense and with a minimum expenditure of time and labor.

A further object of the invention is to provide a machine of this character which automatically effects the dyeing of the yarn or thread during the winding of the yarn on a bobbin. In other words, as the yarn passes from the skein to the bobbin on which it is to be wound it travels through the machine embodying the present invention and is, during its passage through the machine, dyed in the manner described.

Another object is to provide a machine having these advantages and capacities, which may be readily and easily organized with the mechanism for winding the yarn or thread on the bobbins.

Another important object of the invention is to provide a machine of this character which may be readily and easily adjusted to vary the character of the dyeing action thereby facilitating the production of various colored yarn or thread and consequently of producing fabrics or garments of different patterns or color combinations.

Other objects and advantages reside in certain novel features of the construction, arrangement and combination of parts which will be hereinafter more fully described and particularly pointed out in the appended claims, reference being had to the accompany-

ing drawings, forming a part of this specification, and in which:

Figure 1 is a fragmentary view in elevation showing a device for dyeing yarn or thread embodying the present invention and organized with a machine for taking the yarn from a skein and winding it upon a bobbin;

Figure 2 is a view in side elevation looking toward the left of Figure 1;

Figure 3 is a plan view on a larger scale illustrating the construction of the dyeing machine embodying the present invention;

Figure 4 is a view in transverse section on line 4—4 of Figure 3; and

Figures 5 and 6 are detail sectional views taken on lines 5—5 and 6—6, respectively, of Figure 4.

Referring to the drawings and more particularly to Figures 1 and 2, the numeral 1 designates generally a conventional machine 70 widely employed for taking yarn from a skein and winding it upon a bobbin. As shown, the skein S of the yarn is mounted upon a reel R and the yarn is wound upon a bobbin B which is actuated in the usual manner. Between the reel R and the bobbin B the yarn is trained through and guided by conventional guides and tensioning devices, designated at G and G'.

The dyeing device embodying the present invention and designated generally at D, is arranged to operate upon the run of the yarn located between the guide and tensioning device G and the guide G'.

As shown in Figures 3 and 4, the dyeing means comprises a tank or container 1 which contains a suitable supply of dye and which is supported by brackets 2 on the standard A which carries the reel R. Dye applying means is associated with the tank and preferably comprises an applicating roller 3 fixed to rotate with a shaft 4 rotatably mounted in bearings 6 provided on the tank 1. The roller 3 may comprise a wooden body portion 7 equipped with a suitable covering 8, the covering 8 being of fabric of suitable absorbent material adapted to carry a supply of dye and to transfer the same to the yarn. As shown in Figure 4, a portion of the roller 3 is immersed in the supply of dye contained in the

tank and a portion thereof projects above the tank and into position where it is adapted to engage the yarn.

Means is provided for driving the applying roller 3 and comprises suitable gearing between shaft 4 carrying the roller and the mechanism which drives the bobbin B. As shown in Figures 1 and 2, a shaft 10, which is constrained to rotate with the bobbin drive, 10 is connected by chain and sprocket gearing 11 to the shaft 4 so that whenever the bobbin is being rotated to wind the yarn thereon the shaft 4 is actuated to rotate the roller. Obviously, however, an independent motor or 15 other means may be geared to the shaft 4 for driving the same, but to simplify the construction and to obtain best results in the dyeing, the drive of the roller is taken from the bobbin drive.

20 In this connection it is to be understood that, usually, it is desirable to synchronize the roller speed and the yarn speed and this, of course, may be conveniently done by driving the roller from the bobbin actuating mechanism.

25 The present invention proposes to vary the contact of the yarn with the roller 3 to produce a mottled dyeing and a yarn of variegated color. Preferably, this is accomplished 30 by causing the yarn to periodically engage and disengage the roller 3. In carrying out this purpose the yarn, after passing through the guide G, extends down under a rotary yarn shifting device designated generally at 35 15. After passing under the device 15 the yarn extends across the top of the roller 3 through a guide 16. In one phase of the operation the device 15 presses the yarn between it and the guide 16 down to the full line position shown in Figure 4, in which position the yarn engages the periphery of the roller 3. In another phase of the operation the device 15 permits the yarn to rise up to the dotted line position shown in Figure 4 where 40 it is out of contact with the roller 3. The device 15 may be constructed and driven or moved in various ways as its essential operation requires only that its structure and motion be such as to periodically shift the yarn 45 into and out of contact with the roller 3, but, as shown in the drawings it may be made up of a pair of circular cheek plates or end plates 50 17 and 18 secured by means of set screws 19 or other suitable fastening means upon a rotatable shaft 20. The end plate 17 which is of circular form has a circular series of openings 17' around and spaced inwardly of its periphery and the end plate 18 has a similar series of openings 18' arranged in longitudinal alinement with the openings 17' and similar to the openings 17' in all respects except that the openings 18' are internally threaded. Yarn engaging and depressing bars 21 are mounted on the plates 17 and 18, 55 60 65

ings 17' and having their ends 21' externally threaded and engaged with the internal threads of the openings 18' with which they are associated. The ends of the bars 21 received in the openings 17' may have cross slots 21a adapted to coact with a screw driver or the like to facilitate assembly and disassembly of these bars. The bars 21 may be provided in any number and may be spaced at any desired angular interval around the periphery of the device 15. As shown, only three bars are mounted on the plates 17 and 18 and consequently the yarn is caused to engage the roller for only a small period during each revolution of the device 15. It is to be understood, however, that several groups of bars may be provided around the periphery of the plates 17 and 18 and that the bars may be evenly spaced or spaced at different angular intervals as the particular number and arrangement of bars employed depends solely upon the manner in which it is desired to dye the yarn. Thus, the device or means 15 illustrated for displacing the yarn into contact with the rotary dye applying member 80 85 90 is rotary in its character and broadly consists of a rotary member with broken or irregular periphery but it is to be understood that it is not essential that the device 15 be rotary in its character as its function may be accomplished by a similar device which is oscillated, reciprocated or otherwise moved or shifted. However, the rotary device illustrated has many advantages, especially as its action may be so easily varied.

100 The shaft 20, which carries the device 15, is rotatably journaled in adjustable bearing blocks 25 which are slidably fitted in grooves or guide-ways 26 provided upon bearing brackets 27 secured as at 28 to the tank 1 and projecting beyond the rear wall of the tank. The blocks 25 are secured in any adjusted position along their guide-ways by means of clamping screws 29 which have reduced and threaded extensions 30 extending through slots 27' provided in the brackets 27 and underlying the guide-ways 26 and which are threaded into openings 25' provided in the bearing blocks 25. At the juncture of each screw 29 and its reduced extension 30 a shoulder 31 is provided and this shoulder is of such size as to straddle the slot 27' and have binding engagement with the portions of the brackets 27 contiguous with the margins of the slot 27'. By adjusting the blocks 25 along their guide-ways, they may be moved toward or away from the roller 3 and this adjustment varies the angle at which the yarn is led to the roller 3 when subjected to the action of the device 15 and consequently varies the extent of the dyeing action.

110 115 120 125 130 The frequency with which the yarn is depressed into contact with the roller 3 is varied not only by providing more or less depressing bars 21 but by the speed of rotation of the

device 15 carrying these bars 21. For this purpose a change speed gearing is provided between the shaft 4 and the shaft 20. Thus, as shown in Figure 3, a collar 35 is fitted on the shaft 4 so as to be constrained to rotate with the shaft while free to be adjusted longitudinally thereof. If desired, this may be effected by means of a set screw 36. Integrally formed with the collar 35 or otherwise fixed 10 to the shaft 4 are a plurality of driving gear wheels, designated at 37, 38 and 39. In the construction shown, the collar 35 has a web or body plate 40 integral therewith and at its periphery this web is flanged as at 15 41 and the flange is constructed exteriorly to provide the gear wheels 37, 38 and 39 of different diameters. A pinion 42 is fitted on the shaft 20 for axial adjustment although constrained to rotate with the shaft. This 20 may be effected by means of a set screw 43 threaded through the hub of the pinion and having binding engagement with the shaft 20. The pinion 42 may be adjusted along its shaft to be aligned with any one of the gear 25 wheels 37, 38 and 39, and it may be brought into mesh with its aligned gear wheel by adjusting the bearing blocks 25 to move the shaft 20 and the pinion 42 toward or away from the shaft 4 and the driving gears thereof. It is obvious that when the pinion is 30 meshed with the gear wheel 37 the device 15 will be rotated at high speed and any given length of yarn will be periodically brought into more frequent contact with the roller 3 than if the pinion 42 is meshed with either 35 gear wheels 38 or 39. In this way the resulting appearance of the yarn subjected to the dyeing operation is varied. If frequent color variations are desired the gear wheels 37 and 40 42 are meshed and if less frequent variation is desired the gear wheels 38 and 42 or 39 and 42 are meshed.

The dye in the tank 1 is preferably maintained at the proper temperature by means 45 of an electric heater designated generally at 50 and having its casing threaded through one of the side walls of the tank and immersed in the dye. The heating elements are designated at 51 in Figure 4 and are supplied with 55 current from the conductors 52 (see Figure 3).

From the foregoing it will be understood 55 that as the yarn is taken from the reel and wound upon the bobbin it passes through the dyeing device embodying the present invention and that spaced portions in the yarn are brought into contact with the dye applying means shown for the sake of illustration as consisting of a roller 3. The frequency with 60 which the yarn is caused to engage the dye applying means is determined by the rate at which the yarn shifting device 15 is driven and by the number of yarn depressing bars or by the number of groups of such bars provided in the device 15. The extent of yarn

dyed or colored each time that the yarn is depressed into engagement with the dye applying roller is determined by the grouping of the yarn depressing bars 21. It is obvious that if a plurality of bars 21 be provided in 70 closely spaced relation around a portion of the periphery of the device 15 they will hold the yarn against the roller 3 for an appreciable interval and as the yarn is rapidly running past the roller at this time quite an extent of the yarn will be dyed each time the 75 yarn is moved against the roller 3. However, if a lesser number of bars 21 be arranged in each group and each group be spaced around the periphery of the device 15 then portions 80 of the yarn of slight extent only will be dyed each time the yarn is brought into contact with the dye applying roller 3.

But whatever adjustment is effected results in a uniform dyeing of the entire skein 85 of yarn so that when the yarn is subsequently woven or knitted into a fabric a uniform color scheme or mottled effect will be produced.

The invention claimed is:

1. A device of the character described comprising dye applying means, means for causing a fibrous material to travel past said dye applying means, means for periodically moving the fibrous material into engagement with the dye applying means and comprising a rotatable element having means to receive a variable number of yarn engaging and displacing bars at variable angular intervals thereabout.

2. A device of the character described comprising dye applying means, means for causing yarn to travel past said dye applying means and means for periodically moving the yarn into engagement with the dye applying means and comprising a rotatable shaft, and plates carried by the shaft and having means for receiving a plurality of yarn engaging and displacing bars at variable spaced angular intervals about its periphery.

3. A device of the character described comprising dye applying means, means for causing yarn to travel past said dye applying means and means for periodically moving the yarn into engagement with the dye applying means and comprising a rotatable shaft, a pair of end plates fixed to the shaft and having aligned circular series of openings around their peripheries and yarn depressing bars adapted to be assembled with any selected group of openings and periodically engageable with the yarn to cause it to engage the dye applying means.

4. A device of the character described comprising a rotary dye applying member, means for causing fibrous material to travel past said dye applying member, and a rotary means for displacing the fibrous material into engagement with the dye applying member, and means for driving said rotary means

at variable speeds from said rotary dye applying member.

5. A device of the character described comprising a rotary dye applying member, means for causing fibrous material to travel past said dye applying means, and rotary means for displacing the fibrous material into engagement with the dye applying means, and means for driving said rotary means at variable speeds from said rotary dye applying means, and including a plurality of gear wheels of different diameters constrained to rotate with the dye applying means and a driven pinion connected to the displacing means and selectively cooperable with said gear wheels, said displacing means being shiftable toward and away from the dye applying means.

10 6. A device of the character described comprising a rotatable shaft, a rotary dye applying member actuated from the shaft, means for causing fibrous material to travel past said dye applying means, rotary means for periodically displacing said fibrous material into cooperable relation with respect to said 15 dye applying means, and change speed gearing for driving said rotary means from said shaft.

20 7. A device of the character described comprising dye applying means, means for causing fibrous material to travel past said dye applying means, and a rotary device having an irregular and variable periphery directly engageable with the fibrous material to periodically displace it into cooperative relation 25 with respect to the dye applying means.

25 8. A device of the character described comprising a dye applying roller, means for causing fibrous material to travel past said dye applying roller, a rotary device having an 30 irregular periphery engageable with the fibrous material to periodically displace it into engagement with the dye applying roller and means for shifting the rotary device toward and away from the dye applying roller.

35 9. A device of the character described comprising a dye applying member, means for causing material to be dyed to travel past said dye applying member, means for intermittently displacing the material into engagement with the dye applying member and means for driving the displacing means at variable speeds with respect to the travel of said material whereby the character of the dyeing operations may be varied.

40 53. In witness whereof, I hereto affix my signature.

ARTHUR E. BYRD.
